**KEYBOARD FOR AN ELECTRIC ORGAN
OR SIMILAR ARTICLE**

Anthony J. Shabbarsi, 1068 Dewey Ave.,
Rochester, N.Y. 14613

Filed Oct. 9, 1970, Ser. No. 25,409

Term of patent 14 years

Int. Cl. D17—01

U.S. Cl. D56—1

FIG. 1

FIG. 1 is a top plan view of a keyboard for an electric organ or similar article, showing my new design; FIG. 2 is a front elevational view; and

FIG. 3 is a right end elevational view thereof. The broken line showing of an organ case is for illustrative purposes only.

I claim:

The ornamental design for a keyboard for an electric organ or similar article, as shown and described.
